(57) **CLAIM**

The ornamental design for a LED luminaire, as shown and described.

DESCRIPTION

FIG. 1 is a front, right and top perspective view of an embodiment of a lighting device showing the new design incorporating substantially square shape when viewed from the front, including rounded corners and with a curved edge in the transition from the front surfaces to the side surfaces;

FIG. 2 is a bottom plan view thereof;

FIG. 3 is a front elevational view thereof;

FIG. 4 is a top plan view thereof;

FIG. 5 is a right side elevational view thereof;

FIG. 6 is a left side elevational view thereof; and,

FIG. 7 is a back elevational view thereof.
